UNITED STATES PATENT OFFICE.

FRANK A. NIEBERDING, OF DETROIT, MICHIGAN, ASSIGNOR TO ECONOMY STOVE & MANUFACTURING COMPANY, OF DETROIT, MICHIGAN, A PARTNERSHIP.

DESIGN FOR A STOVE.

SPECIFICATION forming part of Design No. 35,381, dated December 3, 1901.

Application filed October 22, 1901. Serial No. 79,602. Term of patent 7 years.

To all whom it may concern:

Be it known that I, FRANK A. NIEBERDING, a citizen of the United States, residing at Detroit, in the county of Wayne and State of Michigan, have invented and produced a certain new and original Design for a Stove, of which the following is a specification, reference being had therein to the accompanying drawing, in which the stove is shown in perspective.

A designates the burner-section, having a flat open-work top B, supported by the curved legs C.

D represents a flat shelf extending parallel with the top B and secured to the legs at a distance beneath the top, as shown.

Rising from the rear edge of the burner-section is a rectangular panel E, having ornamental brackets F and F' at its opposite sides of the same height as the panel and extending at right angles to the latter across a portion of the open-work top of the burner-section, as illustrated. These brackets support a rectangular shelf G, upon which is mounted an oven-section H, overhanging the burner-top, as shown.

I is a door for the oven-section, of ornamental design and provided centrally with an ornamental panel J.

Beneath the oven-section described and depending from the central portion thereof is a broiler-section K, substantially rectangular in configuration and provided with a door L of ornamental design.

The leading feature of the design is a burner-section, the panel rising from the rear edge of said section, the oven-section above the panel and overhanging the top of the burner-section, the supporting-brackets for the oven-section, and a broiler-section depending centrally from the oven.

What I claim as my invention is—

The design for a stove substantially as shown as described.

In testimony whereof I affix my signature in presence of two witnesses.

FRANK A. NIEBERDING.
